UNITED STATES PATENT OFFICE

2,328,492

CINEMATOGRAPHIC REGISTERING APPARATUS

Gerald F. Rackett, Los Angeles, Calif., assignor to Technicolor Motion Picture Corporation, Hollywood, Calif., a corporation of Maine

Application February 7, 1942, Serial No. 429,884

4 Claims. (Cl. 101—130)

In printing motion pictures, whether photographically with light or mechanically by imbibition, it is essential that the printing film be pressed into intimate contact with the film to be printed. In both photographic and mechanical printing the lack of intimate contact results in loss of definition, and in printing by imbibition there is the further difficulty of lack of dye transfer from the printing matrix to the blank film to be printed if the two films are not pressed into intimate contact and retained in that condition while the dye is being imbibed by the blank from the matrix.

Objects of the present invention are to produce registering apparatus which will press two films into intimate contact throughout their entire areas, which is simple and economical to manufacture and which is durable and reliable in use.

According to the present invention the apparatus comprises a register belt having teeth for engagement in the sprocket holes of the films, together with means for feeding the belt along an orbital path including a curved part and a portion leading to the curved part, a seating belt having sprocket holes to receive the teeth, and means for feeding the films and the seating belt to the register belt in the aforesaid portion and thence around the curved part, the pitch of the teeth being approximately a multiple of the pitch of the sprocket holes in the seating belt so that the seating belt is drawn toward the register belt by the fanwise movement of the teeth relatively to each other as the register belt is curved, thereby compressing the films into intimate contact between the two belts. While the register belt preferably has a tooth for every sprocket hole of the films the pitch of the teeth may be two or more times that of the sprocket holes.

For the purpose of illustration a typical embodiment of the invention is illustrated in the accompanying drawing in which:

Fig. 1 is a diagrammatic view of a belt printer of the type referred to;

Fig. 2 is a sectional view of the aforesaid belts and films in the curved part of the orbital path;

Fig. 3 is a section on line 3—3 of Fig. 2;

Fig. 4 is a side view of the right-hand end of the printer; and

Fig. 5 is the section on line 5—5 of Fig. 4.

The particular embodiment of the invention chosen for the purpose of illustration comprises two sheaves 1 and 2 over which is trained an endless belt 3. As shown in Figs. 2 and 3 the register belt 3 comprises a band of approximately the

width and thickness of cinematographic film, the belt preferably being made of metal and carrying register pins or teeth 4 adapted to fit into the sprocket holes of the films. The details of the construction and manufacture of various parts of the apparatus, including the register belt, are disclosed in Patents 1,675,743, 1,704,328, 1,707,695, 1,707,699, 1,707,710, 1,707,733, 1,928,714, 2,257,254 and 2,271,572.

5 For imbibition printing the blank film 5 and a matrix film 6 are fed into superposed contact on the belt, the matrix 6 having first been soaked in dye of the appropriate color and the blank 5 having been conditioned to imbibe the dye from the matrix when the films are pressed into intimate contact on the belt. As disclosed in the aforesaid patents the films 5 and 6 are preferably brought together under water in a tank 7 in order to exclude air bubbles from between the films, the tank having narrow slits for the belt to pass into and out of the tank. Above and below the sheave 2 are guide rolls 8 and 9 pivotally mounted at 10 and 11 on arms 13 and 14, the arms having extensions 15 and 16 cooperating with compression springs 17 and 18 for urging the rolls 8 and 9 toward the sheave 2. At the top and bottom of the machine two other guide rolls 19 and 20 are mounted in line with the rolls 8 and 9. Trained over the rolls 8, 9, 19 and 20 is a seating belt 21 similar to the register belt 3 except in that no register pins are mounted in its sprocket holes. The seating belt travels in the direction of the arrow in Fig. 4 and after passing over the roller 8 it feeds into superposition to the films 5 and 6 on the register belt 3 (Fig. 3).

20 As shown in Fig. 5 the sheave 2 has a rubber rim 22 with circumferential recesses at the sides to accommodate the heads of the pins 4. The roller 8 has flanges 23 immediately inside the rows of register teeth and rings 24 secured to the flanges by screws 25 outside the rows of register teeth. Intermediate the flanges 23 and the rings 24 are rings 26 which have notches in their outer peripheries to accommodate the projecting ends of the teeth 4.

25 In operation the two films 5 and 6 are fed to the belt in the straight portion of its orbital path immediately in advance of the point where the belt starts around the curved portion of its orbit at the sheave 2. At this point or slightly in advance of this point the seating belt 21 is fed to the register belt in superposition to the two films, the two belts and the films being pressed together by the spring 17 acting through roller 8. 30 As the seating belt enters the curved portion of

its orbit the projecting ends of the register teeth 4 move apart fanwise owing to the curvature of the register belt (Fig. 2). This tends to draw the seating belt toward the center of the curved path, which in turn tightly compresses the two films between the two belts. By making the seating belt of metal its stretchability can be minimized and by suitably predetermining the pitch of the sprocket holes in the seating belt any desired amount of compression between the two films can be secured. In most cases the pitch of the holes in the seating belt may be the same as that of the register belt and films.

After the films have thus been tightly pressed together they remain in intimate contact due to their wet condition until they are peeled apart at the roller 21, the printed film being removed from the belt at the roller 28. As disclosed in the aforementioned patents the distance between rollers 9 and 27 is great enough to permit the dye transfer to be completed before the films are peeled apart.

It should be understood that the present disclosure is for the purpose of illustration only and that this invention includes all modifications and equivalents which fall within the scope of the appended claims.

I claim:

1. Apparatus for registering one film with another film comprising a register belt having teeth for engagement in the sprocket holes of the films, means for guiding the belt along an orbital path including a curved part and a portion leading to the curved part, a seating belt having sprocket holes to receive said teeth, means for feeding the films and the seating belt to said register belt in said portion and thence around the curved part, the pitch of said teeth being approximately a multiple of the pitch of the sprocket holes in the seating belt so that, in said curved part, the seating belt is drawn toward the register belt by the fanwise movement of the teeth relatively to each other as the register belt is curved, whereby the films are compressed into intimate contact between the two belts.

2. Apparatus for registering one film with another film comprising an endless register belt having teeth for engagement in the sprocket holes of the films, means for guiding the belt along an orbital path including a curved part and a por-

tion leading to the curved part, an endless seating belt having sprocket holes to receive said teeth, means for feeding the films and the seating belt to said register belt in said portion and thence around the curved part, the pitch of said teeth being approximately a multiple of the pitch of the sprocket holes in the seating belt so that, in said curved part, the seating belt is drawn toward the register belt by the fanwise movement of the teeth relatively to each other as the register belt is curved, whereby the films are compressed into intimate contact between the two belts.

3. Apparatus for registering one film with another film comprising a register belt having teeth for engagement in the sprocket holes of the films, means for guiding the belt along an orbital path including a curved part and a portion leading to the curved part, a seating belt having sprocket holes to receive said teeth, means for feeding the films and the seating belt to said register belt in said portion and thence around the curved part, the pitch of said teeth being approximately equal to the pitch of the sprocket holes in the seating belt so that, in said curved part, the seating belt is drawn toward the register belt by the fanwise movement of the teeth relatively to each other as the register belt is curved, whereby the films are compressed into intimate contact between the two belts.

4. Apparatus for registering dye-absorptive film with a matrix film comprising a register belt having teeth for engagement in the sprocket holes of the films, means for guiding the belt along an orbital path including a curved part and a portion leading to the curved part, a seating belt having sprocket holes to receive said teeth, means for feeding the films and the seating belt to said register belt in said portion and thence around the curved part, the pitch of said teeth being approximately a multiple of the pitch of the sprocket holes in the seating belt so that, in said curved part, the seating belt is drawn toward the register belt by the fanwise movement of the teeth relatively to each other as the register belt is curved, whereby the films are compressed into intimate contact between the two belts.

GERALD F. RACKETT.
